CLAIM

The ornamental design for a compressible feeding apparatus, as shown and described.

DESCRIPTION

FIG. 1 is a top, front, and left perspective view of a compressible feeding apparatus showing our new design;

FIG. 2 is a front elevational view thereof;

FIG. 3 is a right side, elevational view thereof, the left side being a mirror image of that shown;

FIG. 4 is a rear elevational view thereof;

FIG. 5 is a top plan view thereof; and,

FIG. 6 is a bottom plan view thereof.

In FIGS. 2-5 the cap is removed for ease of illustration.

FIG. 1

FIG. 2

FIG. 3

FIG. 4

FIG. 5

FIG. 6
